J. W. THOMAS,
RAIL HOLDING DEVICE.
APPLICATION FILED NOV. 19, 1915.

1,227,857.

Patented May 29, 1917.

UNITED STATES PATENT OFFICE.

JOHN W. THOMAS, OF CHICAGO, ILLINOIS, ASSIGNEE TO THE THOMAS RAILWAY TRACK APPLIANCE COMPANY, A CORPORATION OF KANSAS.

RAIL-HOLDING DEVICE.

1,227,857.

Specification of Letters Patent. Patented May 29, 1917.

Application filed November 19, 1915. Serial No. 62,388.

To all whom it may concern:

Be it known that I, JOHN W. THOMAS, a citizen of the United States, residing at Chicago, in the county of Cook and State of Illinois, have invented certain new and useful Improvements in Rail-Holding Devices, of which the following is a specification.

My invention relates to rail holding appliances, and my object is to provide a simple and inexpensive device of this character whereby a rail is securely held from rattling, tipping laterally, or creeping longitudinally.

In order that the invention may be fully understood, reference will now be made to the accompanying drawing, in which:

Figure 1 is a cross section of a rail held in position by my invention.

Fig. 2 is a horizontal section on line II-II of Fig. 1, with some of the parts removed.

Fig. 3 is a broken, inverted plan view of a tie-plate and fastening device employed in carrying out my invention.

Fig. 4 is a broken, vertical section on line IV-IV of Fig. 1.

Fig. 5 is a detail of the fastening device constituting an important feature of the invention.

Fig. 6 is a horizontal section on line VI-VI of Fig. 5.

Fig. 7 is a detail end view of the tie-plate. A designates a rail of usual construction.

1 designates a tie-plate adapted to be secured to an under-lying cross-tie B with spikes C. Said tie-plate is provided near one side with a lip 2 and near its opposite side with an abutment 2^a, having a beveled upper surface 2^c.

3 designates slots extending through the tie-plate 1 adjacent the abutment 2^a to receive fastening devices 4, which coact with the lip 2 in firmly securing the rail A upon the tie-plate 1. Two diagonal corners at the underside of each slot 3, are beveled as indicated at 3^a, to tighten the fastening devices 4, as will be hereinafter shown.

Each fastening device 4 in the present instance, consists of a shank 5, a shouldered member 6 depending from said shank 5, a head 7, and an eccentric portion 8, interposed between the shank 5 and the head 7, and provided with a lug 8^a.

The shouldered member 6, in plan view, is

of approximately the same shape as the slots 3 and adapted to pass therethrough when turned longitudinally thereof, as disclosed at the lower portion of Fig. 3. The head 7 is of proper form to overlap the adjacent flange of the rail base when said head is turned in the direction disclosed by Fig. 1.

In practice, the rail A is placed in position upon the tie-plate 1 with one of its base flanges underlying the lip 2 and its other base flange lying upon the upper bevel edge 2^c of the abutment 2^a. Pressure is then applied to the raised base flange to force it down off the bevel edge 2^c, and seat the base squarely upon the tie-plate 1. The two fastening devices 4 are then placed in position in the slots 3 and turned one quarter of a revolution to cause the heads 7 to overlap the adjacent base flange. This operation requires more or less force as the original inclination of the under surface of the heads 7 is slightly less than the inclination of the upper surface of the rail base in order that when said heads are turned to the position disclosed by Fig. 1, they will bear firmly upon the flange of the rail base and force the latter so firmly into contact with the surface of the tie-plate as to prevent the rail from creeping longitudinally. The turning of the fastening devices 4 causes the shouldered members 6 to travel down the bevel corners 3^a of the slots 3, and coact with the heads 7 in firmly binding the rail A upon the tie-plate 1, so that said rail cannot rattle or creep longitudinally. The turning of the fastening devices 4 also brings their eccentric portions 8 against the adjacent margin of the rail base which is forced laterally thereby until firmly seated beneath the lip 2. After the rail has been thus firmly secured upon the tie-plate 1, the latter is secured to the cross-tie B with the spikes C, and as said spikes are hammered down into the cross-tie B the attenuated lower margins 6^a of the members 6 are forced down into said cross-tie and thus secure the fastening devices from rotating and loosening their grip upon the rail and the tie-plate. As a further precautionary measure the lugs 8^a are adjusted against the spikes C, so that the fastening devices 4 cannot turn and get loose until said spikes are withdrawn from the cross-tie B.

Having thus described my invention,

what I claim and desire to secure by Letters Patent, is:

1. In a device of the character described, a tie-plate having a rail-engaging member at one side and an opening at its opposite side, and a fastening device rotatably arranged within said opening and embodying rail-holding means, and an edged member which latter is adapted to be embedded in an underlying cross tie.
2. In a device of the character described, a tie-plate, and a rail fastening device rotatably mounted in said tie-plate and embodying a nonthreaded shouldered member of greater width than depth adapted to be embedded in an underlying cross-tie, for the purpose described.
3. In a device of the character described, a tie-plate having a spike hole therein, and

a rail fastening device rotatably mounted 20 within said tie-plate and embodying a lug extending at an angle thereto and adapted to abut a spike driven into said spike hole for holding the tie-plate in position, substantially as described.

25

4. A rail fastening device consisting of a cylindrical portion, an edge-shaped portion depending from said cylindrical portion, an eccentric portion surmounting said cylindrical portion, and a head surmounting said eccentric portion and adapted to overlap a rail base.

30

In testimony whereof I affix my signature, in the presence of two witnesses.

JOHN W. THOMAS.

Witnesses:

F. G. FISCHER,
L. J. FISCHER.
